FRAME FOR A MERCHANTISING DISPLAY
STAND FOR WRITING INSTRUMENTS AND THE LIKE

Frank H. Stephens, Jr., Dunwoody, Ga., assignor to Scripto, Inc., a corporation of Georgia

Filed Oct. 31, 1966, Ser. No. 4,480

Term of patent 14 years

(Cl. D80—9)

FIG. 1

FIG. 3

FIG. 1 is a front elevational view of the frame for a merchandising display stand for writing instruments and the like embodying my new design;

FIG. 2 is a side elevational view; and,

FIG. 3 is a top plan view thereof.

The writing instrument holders disclosed in FIGURES 1-3 have been shown in broken lines for purposes of illustration only.

I claim:

The ornamental design for a frame for a merchandising display stand for writing instruments and the like, as shown and described.
